UNITED STATES PATENT OFFICE.

JOHN A. FERG, OF NORFOLK, VIRGINIA, ASSIGNOR OF ONE-HALF TO JOHN A. SMITH, OF SAME PLACE.

PUZZLE-STOPPER FOR CONFECTIONERY-BOTTLES.

SPECIFICATION forming part of Letters Patent No. 554,920, dated February 18, 1896.

Application filed September 4, 1895. Serial No. 531,445. (No model.)

To all whom it may concern:

Be it known that I, JOHN ADAM FERG, a citizen of the United States, residing at Norfolk, in the county of Norfolk and State of Virginia, have invented a new Puzzle-Stopper for Confectionery-Bottles, of which the following is a specification.

I attain the results desired by the means which are illustrated in the accompanying drawings, in which—

Figure 1 is a vertical section of the whole mechanism; Fig. 2, side, top, and bottom views of the stopper proper; Fig. 3, a side view of key, and Fig. 4 a side and top view of bushing.

Similar letters refer to similar parts throughout the several views.

Fig. 1: A represents the bottle, B the stopper, C the bushing, D the key, and E a cap covering key, the stopper, bushing, key, and cap all being full size.

Fig. 2: B represents a side view, R a top view, and S a bottom view, of the stopper, which is turned of wood. The dotted lines of B show y as a countersink to allow ring a of key, Fig. 3, to fall to either side and reduce the height of cap; the vertical lines, the hole through stopper in which bushing C of Fig. 4 is inserted; x, a square recess or countersink, and z z grooves cut directly opposite each other and tapering from hole in which bushing is inserted to circumference of square recess to allow tumblers of key to fall through to bottom of recess, and thus avoiding unnecessary length of key and play between square recess x and countersink y. The vertical dotted lines at x show full depth of square recess. The bottom of stopper being larger than mouth of bottle, it is cut into six sections to allow inserting it into mouth of bottle, (the sections being shown in R and S,) a, b, and c being three equal sections, f and d two equal sections, and e a wedge or final section, the four cuts or lines of sections a, b, and c being to the center and the two cuts or lines of section e out of the center, as shown, the inner circumference being larger than the outer, the sections f, a, b, c, and d being larger on the outer circumference. The sections cut in this way, with the hole in center of stopper, as shown, easily allows the insertion of

the different parts into mouth of bottle. In the bottom view S of Fig. 2, z shows full-size grooves, cut only in wedge e and section b, through which tumblers of key fall. The 55 stopper, as shown in sectional view, Fig. 1, is not intended to fit too snugly between top of bottle and the rounding or inner neck of bottle.

Fig. 3: D represents a full-size side view of 60 the key, which is made of iron; a, a loose ring; b, the tumblers, and c the pins on which tumblers hinge. The ring is inserted into key loosely, so that it can fall to either side and reduce height of cap. The tumblers b b 65 of key, as shown in Fig. 1, are rounded on the upper and square on lower corners, the holes in tumblers being close to upper round corners and held in position by two rivets or pins c c, on which the tumblers hinge, the tumblers being so set and hinged that when bottle stands upright they can only fall in a horizontal position to the bottom of recess. The V-shaped portion of key directly above the tumblers is so shaped that when inserting the 75 key into the hole of stopper the tumblers which lie against it will very readily fall into position and lock stopper. To unlock stopper and solve the puzzle, the bottle must be turned upside down and key turned to tapering, which can then be easily removed.

Fig. 4: C shows side and top views of a solid wooden bushing, the hole in same being to admit key, which fits loosely. When key is 85 in position in the hole of bushing, the ring is inserted into hole of the upper portion of key, thus holding the bushing and key together, the object of the bushing, as shown in Fig. 1, being to hold the different sections of stopper 90 firmly and also the key in its proper position. The space between bushing and square recess of stopper is to permit tumblers of key to work freely.

Fig. 1: E is a cap-piece, and is intended to 95 conceal ring of key and to make the whole look neater.

Having thus described the invention, I claim—

1. In a puzzle-stopper for bottles the combination of a stopper so turned as to fit the mouth or neck of the bottle, the top being

countersunk to admit a key-ring to fall either way to reduce height of cap, a solid ring forming a portion of the stopper with shoulder to rest on mouth of bottle, an enlarged bottom portion larger than the neck of the bottle, a round hole through the stopper with a square recess and two taper-grooves at the bottom opposite each other and tapering from the round hole to the circumference of the recess, 5 said taper being sufficient to allow the tumblers of the key to fall through easily and engage in said recess, substantially as described. 10 2. In a puzzle-stopper for bottles the combination of a stopper provided with a longi-

tudinal opening, a stopper-bushing adapted 15 to rest on the top of the bottle for holding the stopper and having taper-grooves, a key provided with a ring and two tumblers loosely attached to the key with pins, thus allowing the tumblers to assume a horizontal position 20 when the bottle stands upright, said key passing through the holes in the stopper substantially as described.

JOHN A. FERG.
